(57) **CLAIM**

The ornamental design for a lock assembly component, as shown and described.

DESCRIPTION

FIG. 1 is a perspective view of a lock assembly component according to my new design;

FIG. 2 is a second perspective view of the lock assembly component of FIG. 1;

FIG. 3 is a left-side elevational view of the lock assembly component of FIG. 1, the right-side elevational view being a mirror image thereof;

FIG. 4 is a front elevational view of the lock assembly component of FIG. 1, the rear elevational view being a mirror image thereof;

FIG. 5 is a top plan view of the lock assembly component of FIG. 1; and,

FIG. 6 is a bottom plan view of the lock assembly component of FIG. 1.

The broken lines in FIG. 1 represent environment and are for illustrative purposes only and do not constitute part of the claimed design.
